11 Claims. (Cl. 196—53)

It is known that hydrocarbons, for instance mineral oils, are decomposed by distillation at higher temperatures, with the formation, on the one hand, of substances of a lower boiling point 5 and gases, and on the other hand, of carbon and substances having a higher boiling point than the initial materials. This action is made use of in practice in the well-known cracking process for the production of benzine from mineral oils. 10 In the known processes of this kind, however, the yields are comparatively small, because numerous less valuable and undesired by-products are produced.

The yields in liquid hydrocarbons of low boiling 15 point are also sometimes unsatisfactory when carrying out the operation in the presence of hydrogen, even when working under pressure, and especially when carrying out the process on a large industrial scale, and moreover troubles 20 may occur in the course of the operation.

We have now found that excellent yields, especially in hydrocarbons of low boiling point are obtained, if carbonaceous liquids, by which are understood pastes with coal and other solid fuels, 25 tars, mineral oils, their distillation and conversion products and residues and the like, are subjected chiefly in the liquid state to a treatment by heat in the presence of catalysts and under any desired pressure, and the products thus obtained 30 are passed in the vaporous and preferably in a superheated state over catalysts. By this manner of working it is possible to carry out the heat treatment of the initial substances in a liquid state at lower temperatures than are required in the usual cracking or destructive hydro- 35 genation processes for the production of products of low boiling point whether carried out with or without pressure. The operation at lower temperatures has the particular advantage, that 40 the deposition of carbon and the formation of gases, for instance of methane, are remarkably diminished. Either the first stage of heat treatment or the second stage of treating the preferably superheated vapors or both operations may 45 be carried out, if so desired, in the presence of inert gases or of gases participating in the reaction, or mixtures of such, especially in the presence of hydrogen or gases giving off hydro- 50 gen. Instead of, or besides hydrogen, also water vapor, carbon dioxide, carbon monoxid, nitrogen or gases such as ammonia, which act catalytically, may be employed as gases to be added. The process can be carried out at any desired pressure, but particularly advantageous results 55 are obtained when working with streaming hy-

drogen in excess, that means under a high partial pressure, and employing elevated pressure.

In the first stage of the process the temperature employed will generally range between about 300° and 500° C.; it may, however, in some cases 5 also be outside the said range, as it depends on the nature of the initial material, especially on its contents in asphaltic materials, and on the other conditions of working. The temperature employed in the second stage depends on the nature of the intermediate products to be treated; 10 it will generally be about from 50° and 100° C. higher than that employed in the first stage of the process. It is to be understood that the temperature employed with one kind of initial material in the first stage may be higher than those employed in the second stage with another kind of initial material.

The pressure under which the process is carried out may be varied as desired; it may be reduced or atmospheric pressure, or it may be elevated, for example 5, 20, 50, 100 or even more atmospheres. It may also be advantageous to carry out the second stage of the process under another pressure than the first stage. 20 25

The catalysts should comprise one or more elements of the second to the eighth group of the periodic system or compounds thereof. They may be of metallic or non-metallic nature, and may be employed in the form of smooth surfaces, 30 or of wires, filings, porous pieces or in the form of powder, and with or without supports. As examples of metals we mention molybdenum, tungsten, aluminium, cobalt, and alloys especially of the heavy metals, for instance, highly al- 35loyed, if necessary thermally pretreated steels; other suitable catalysts are for example tungstic acid, molybdic acid, aluminium hydroxid, bauxite, active charcoal, alderwood-charcoal which has been thoroughly glowed out, pine wood-charcoal, titanic acid aluminium silicates, man- 40 ganous oxid, uranium aluminate silicate, mixtures of reduced copper and iron oxids, diatomaceous earth, pumice stone and the like. The catalysts hereinbefore mentioned will be em- 45 ployed in either stage of the process.

In the first stage of the process in which the initial substances are treated mainly in the liquid state, the catalysts are preferably added to the initial materials in the form of powder, whereas 50 porous contact bodies are preferably employed in the second stage, which is the treatment in the vapor state of the products obtained.

It is advisable in carrying out the process according to the present invention to keep the hot 55

zone of the apparatus free from such substances as would give rise to a deposition of carbon and to the formation of methane. Further, the material for the walls of the reaction vessel should be 5 so chosen as to be resistant to sulfur and oxygen, for instance the same may be made of or lined with aluminium or highly alloyed steels, especially after thermal pretreatment of the latter. Our 10 said invention will be further illustrated with reference to the accompanying drawing showing a side elevation partly in section of an apparatus especially suitable for carrying out the process according to the present invention. Fresh gas is introduced through a valve A' by way of a pipe 15 B into a pipe C through which the carbonaceous liquids to be treated are passed. Gases which have already passed through the whole process are returned in circulation and introduced into the pipe C at S'. The mixture is passed through a 20 coil F arranged in a preheater G and is introduced at E into a stirring vessel J containing a catalyst, where the treatment essentially in the liquid phase takes place. The products are taken off from the said vessel at H and introduced into a 25 reaction vessel containing a catalyst at K in which vessel the reaction is carried out in the vapor state. The reaction product is then passed through the pipe L to a condenser M where the greater portion of the liquid products are recovered 30 and the gases are then further passed through a stripping vessel N where the rest of the liquid products are recovered. The gases emerging from the stripping vessel at O are passed through a circulatory pump P and are then returned to the process at S'.

The following example will further illustrate how our invention may be carried out in practice, but the invention is not limited to this example.

Example

Preheated lignite tar is continuously forced into a vertically arranged high pressure reaction vessel, the hot parts of which are lined with aluminium. The lower part of the vessel is maintained at about 420° C. Hydrogen in excess is passed at 200 atmospheres through the liquid reaction mass containing from 1 to 5 per cent of Florida earth in a fine state of division, while 45 stirring. The vapors thus produced, which contain comparatively little benzine, and consist chiefly of middle oils, are immediately passed in the upper portion of said reaction vessel at 480° C. over a porous catalyst prepared by reducing a 50 mixture of molybdc acid and zinc oxid which is permanently arranged in the apparatus. On cooling the gases and vapors leaving the reaction vessel, a product containing about 80 per cent of benzine is obtained in a brisk operation, by a 55 single treatment of the initial material without the formation of coke or a substantial formation of methane.

The hydrogen is advantageously pumped round in a circulatory system, the consumed portion being made up for by the addition of fresh gas.

Instead of carrying out the catalytic treatment of the vapors immediately after the first stage treatment in the same reaction vessel, the intermediate products may be condensed and subjected 60 separately to the treatment described in a second apparatus.

Other tars, pitches, petroleum residues, pastes with coal, lignite, and the like, in hydrocarbons or other liquid media may be treated in the same 65 way as lignite tar and with similar results.

In our copending application Ser. No. 86,646, filed February 6th, 1929 we have disclosed, among other things, a two-stage process for converting carbonaceous materials of the nature of solid and liquid fuels, distillation and extraction products thereof, into low boiling oils by a two-stage process. Example 9 of that application discloses a process according to which lignite, alone or mixed with oil, is treated with hydrogen under a pressure of 200 atmospheres and at a temperature of about 480° C. and the products resulting from this treatment are passed in the vapor phase over calcium carbonate, for which a catalyst of more precious character can be substituted, under the same pressure as used in the first stage and 10 at a temperature ranging from 500° to 550° C. The disclosure of this particular type of a two-stage process is common to Ser. No. 86,646 and this application. This particular procedure is covered by the claims of this application. To 15 that extent, therefore, this application is a continuation in part of Ser. No. 86,646.

What we claim is:

1. The process of converting a substance of the nature of coal tar into lower boiling hydrocarbons which comprises subjecting the said tar in the liquid phase to a heat-treatment at a temperature of about 420° C., under a pressure of about 200 atmospheres and in the presence of hydrogen and then passing the vapors evolved 30 from said tar at a temperature of about 480° C. and under substantially the same pressure over a catalyst comprising molybdc acid and zinc oxide.

2. A combination process for producing valuable low boiling hydrocarbons from higher boiling oils capable of several stages of conversion, comprising the destructive hydrogenation of such oil in the liquid phase at a relatively low destructive hydrogenation temperature whereby oil of low 40 boiling and intermediate boiling fractions containing comparatively little benzines is produced, separating such fractions and then converting the intermediate fractions in the vapor phase into a low boiling distillate consisting chiefly of benzines 45 at a destructive hydrogenation temperature from 50 to 100° C. higher than the temperature used in the first stage in the presence of a catalyst capable of promoting the cracking of hydrocarbons.

3. Process according to claim 2 in which the 50 first step is accomplished at a temperature within the approximate range of 300 to 500° C.

4. Process according to claim 2, in which destructive hydrogenation and conversion of the intermediate hydrogenation product to low boiling hydrocarbons are carried out under the influence of catalytic materials immune to sulfur poisoning.

5. An improved process for producing valuable 60 low boiling distillates from heavier hydrocarbon oil capable of several stages of conversion, which comprises subjecting such oil in the liquid phase to destructive hydrogenation in the presence of a sulfactive catalyst in a primary zone under pressure in excess of 20 atmospheres and at temperature of 300° C. to about 500° C. for a time sufficient to convert a part of the oil into naphtha and a part thereof into heavier intermediate oil, separating such fractions, and then subjecting the heavier intermediate oil to destructive hydrogenation in vapor phase over a sulfactive catalyst in a secondary zone at a temperature from 50° to 100° C. above that used in the primary zone and between the limits of 350° and 600° C.

6. An improved process for obtaining valuable 75

low boiling oils from heavier hydrocarbon oils, residues and the like capable of several stages of conversion, which comprises subjecting the heavy oil to distillation in presence of hydrogen and a sulfactive catalyst, under pressure in excess of 100 atmospheres and at temperatures from 300° to 500° C. whereby naphtha and a heavier intermediate fraction are obtained as distillates, separating these fractions, and then treating the heavier oil in the vapor phase over a sulfactive catalyst with hydrogen under pressure in excess of 100 atmospheres and at a temperature from about 50° to 100° C. higher than that used in the first stage, whereby it is converted largely into low boiling oil.

7. The process of converting liquid hydrocarbons capable of several stages of conversion into lower boiling hydrocarbons which comprises subjecting the said hydrocarbons, chiefly in the liquid state, to a temperature between 300° and 500° C. until the said initial material is substantially completely converted chiefly into a lower boiling oil containing comparatively little benzine and then passing the resulting lower boiling products in the vapor state at a temperature which is higher than the temperature used in the first stage by from 50° to 100° C. over a catalyst comprising at least one metal selected from groups 3 to 8 of the periodic system capable of promoting the cracking of the hydrocarbons.

8. The process of converting liquid hydrocarbons capable of several stages of conversion into lower boiling hydrocarbons which comprises subjecting the said hydrocarbons, chiefly in the liquid state, to a temperature between 300° and 500° C. until the said initial material is substantially completely converted chiefly into a lower boiling oil containing comparatively little benzine and then passing the resulting lower boiling products in the vapor state at a temperature which is higher than the temperature used in the first stage by from 50° to 100° C. over a catalyst com-

prising at least one metal selected from groups 3 to 8 of the periodic system capable of promoting the cracking of the hydrocarbons, hydrogen being employed in at least one of the two stages of the process.

9. The process of converting liquid hydrocarbons capable of several stages of conversion into lower boiling hydrocarbons which comprises subjecting the said hydrocarbons, chiefly in the liquid state, to a temperature between 300° and 500° C. until the said initial material is substantially completely converted chiefly into a lower boiling oil containing comparatively little benzine and then passing the resulting lower boiling products in the vapor state at a temperature which is higher than the temperature used in the first stage by from 50° to 100° C. over a catalyst comprising at least one metal selected from groups 3 to 8 of the periodic system capable of promoting the cracking of the hydrocarbons, both stages being carried out under a high pressure and hydrogen being present in at least one of the two stages.

10. A process as defined in claim 2 wherein the catalyst employed in the second stage comprises at least one metal selected from groups two to eight of the periodic system.

11. A process for the destructive hydrogenation of hydrocarbon oil which comprises introducing said oil into a reaction zone maintained under temperature and pressure conditions adequate to effect liquid phase conversion and hydrogenation therein, introducing sufficient hydrogen-containing gas directly into the liquid oil in said reaction zone to effect hydrogenation thereof, removing vaporous reaction products from said zone and introducing the same into a secondary reaction zone and reacting the vaporous reaction products in said secondary zone with hydrogen-containing gas to effect further hydrogenation thereof.
